United States Patent Office.

GEORGE E. WHITMORE, OF HOUSATONIC, MASSACHUSETTS.

Letters Patent No. 65,520, dated June 4, 1867

IMPROVED FOLDING CHAIR.

The Schedule referred to in these Letters Patent and making part of the same.

TO ALL WHOM IT MAY CONCERN:

Be it known that I, GEORGE E. WHITMORE, of Housatonic, in the county of Berkshire, and State of Massachusetts, have invented a new and useful improvement in Camp or Folding Chairs; and I do hereby declare that the following is a full, clear, and exact description thereof, reference being had to the accompanying drawing, through letters of reference marked thereon; forming part of this specification, and in which—

Figure 1 represents a perspective view of a chair constructed on my plan.

Figure 2, a vertical section of the lower end of one of the arm-posts.

Figure 3, a perspective view of the same.

Figure 4, a similar view of one of the wrists formed upon the headers of the cross-legs.

The same parts occurring in the several figures are indicated by the same letters.

My improvement consists in a novel construction and combination of parts, whereby a more solid and durable chair is produced, and which can also be folded more compactly than those heretofore made.

To enable others to make and use my invention, I will proceed to describe it by referring to the drawings, in which—

C represents the cross-legs, connected together by the usual cross-ties at or near the lower end, and pivot-bar at their mid-length. A A represent the headers, which connect and are firmly attached to the upper ends of each pair of legs. On each of these headers are formed two wrists E, fig. 4, to which are attached the arm and back-posts B B by means of straps D passed around them and secured to the stub end of the posts B by screws, bolts, or other suitable means. These straps D have slots G formed in that portion which encircles the wrist E for the insertion of a fixed stop-pin to prevent the arms folding in beyond the desired position.

Having thus described my invention, what I claim as new, and desire to secure by Letters Patent, is—

The combination of the arm-posts B, straps D, and headers A with their stop-pins and slots G, constructed and arranged in a folding chair in the manner and for the purpose set forth.

GEO. E. WHITMORE.
